UNITED STATES PATENT OFFICE.

CHARLES SALATHE, OF NEW YORK, N. Y., ASSIGNOR TO THE ADHESIVE GIMP COMPANY, (LIMITED,) OF SAME PLACE.

DESIGN FOR GIMP.

SPECIFICATION forming part of Design No. 19,531, dated December 24, 1889.

Application filed November 25, 1889. Serial No. 331,553. Term of patent 3½ years.

To all whom it may concern:

Be it known that I, CHARLES SALATHE, of the city, county, and State of New York, have invented and produced a new and original

5 Design for Gimp, of which the following is a specification, reference being had to the accompanying drawing, forming part thereof.

The said drawing is a face view of a piece of gimp showing my said design.

10 The said design consists of the longitudinal puffing lays or bands $\alpha\alpha'$, transverse bars α^2 ,

crossing the bands $\alpha\alpha'$, a chain ornament α^3 , extending longitudinally along the center of the gimp, and the longitudinal cord ornaments $\alpha^4\alpha^5$ adjacent to the edges thereof. 15

What I claim is—

The design for gimp, substantially as described and shown.

CHARLES SALATHE.
